UNITED STATES PATENT OFFICE.

EDWARD C. WILSON, OF OAK PARK, ILLINOIS, ASSIGNEE TO HEMPHILL COMPANY, OF CENTRAL FALLS, RHODE ISLAND, A CORPORATION OF MASSACHUSETTS.

STOCKING AND METHOD OF MAKING SAME.

Application filed August 26, 1922, Serial No. 584,496. Renewed May 10, 1924.

This invention relates to stockings and to the method of making the same. In order that the principle of the invention may be readily understood, I have disclosed in the 5 drawing a single embodiment of the stocking and will describe the best mode known to me for making the same without limiting my invention thereto.

In the drawing:

10 Fig. 1 is a side elevation of one embodiment of the invention;

Fig. 2 is an outside view on a larger scale of a part of the back of the stocking at the high splice region;

15 Fig. 3 is a similar view of the inside of the stocking at the high splice region; and

Fig. 4 is a somewhat diagrammatic detail indicating the formation of some of the 20 stitches of the main and reinforcing threads and the floated portions of said reinforcing thread.

The stocking of my invention is preferably a so-called circular or seamless stocking knitted upon a circular machine having 25 means to form the heel and toe pockets, such as narrowing and widening pickers. While any suitable mechanism may be employed in the production of the stocking, the machine should be equipped with means for introducing the main knitting yarn, and for introducing reinforcing yarns at desired 30 points. My invention pertains more particularly to the knitting of a reinforcement or reinforcing area having non-parallel sides. In the disclosed embodiment of the 35 invention, the reinforcing area is located at the back of the heel and is of a general triangular shape with the apex pointing upward and on the back median line of the stocking. I will describe the disclosed embodiment of the invention without specifically limiting myself thereto as to all aspects of the invention.

40 The stockings may be begun at the top 1 of the leg or at the top line 2 of the toe. Assuming merely for brevity of description that the stocking is begun at the top 1 of the leg, it is knitted preferably by rotary knitting throughout excepting for the heel and 45 toe pockets which are made by narrowing and widening in any suitable manner, as by the use of narrowing and widening pickers. The stocking may have a garter top or welt portion indicated at 3, and the yarn may 50 be changed during the formation of the

stocking as desired, and the length of the stitches may be changed at a number of points as the knitting progresses, so as to aid in giving shape or form to the stocking in the knitting operation. 60

It is customary in the knitting of stockings to substitute for the main yarn a high splice yarn or to introduce a reinforcing yarn for the high splice area above the heel, the yarn being again changed if desired at 65 the commencement of the heel. In accordance with the disclosed embodiment of the invention I provide a reinforcing or high splice area in an improved manner and in such a way as to produce an entirely acceptable article more readily than it has heretofore been made. 70

When the point 4 has been reached at the top of a high splice area 5, I introduce a reinforcing yarn of any suitable character 75 and in any suitable manner as by providing a yarn feeding finger carrying the high splice yarn and providing an additional cam which will depress all the needles in the vicinity of the high splice yarn finger excepting those that are to take the high splice yarn and in successive courses varying the number of needles which are to receive the high splice yarn or the said high splice yarn may be suitably introduced by movement of the high splice yarn finger. Regardless of 80 the precise manner for controlling the knitting of the reinforcing yarn upon a successively and preferably constantly increasing number of needles in successive courses, I so manipulate the needles and the reinforcing or high splice yarn guide in relation 85 to each other as to cause the reinforcing or high splice yarn to be taken by a minimum number of needles at the point 4, as, for example, one, two or four needles, and in the succeeding courses, of any desired number, I gradually increase and in desirably regular order the number of needles taking the reinforcing or high splice yarn and continue 90 this operation until the top of the heel is reached at the line 6—6, after which the high splice yarn is herein withdrawn and the heel yarn is introduced. 95

100 The high splice yarn which is indicated at 7 in Fig. 4, is knitted in with the main yarn 8 as shown in said figure to produce the triangular or other reinforcing area, and from the end of each partial course throughout 105 the entire formation of the triangular or 110

other reinforcing area, the reinforcing yarn 7 is floated directly to the opposite end of the next succeeding course, as clearly indicated in Fig. 3 at 9, the said figure being, as 5 stated, an inside view of the stocking. Thus the stocking presents a triangular or other suitably shaped reinforcing area wherein the high splice or reinforcing yarn is knitted in with the main yarn, and from edge to 10 edge of the said high splice or reinforcing area the reinforcing or high splice yarn is floated directly across but is left unimpaired or intact throughout the entire reinforcing or high splice area and is of the 15 short, but gradually increasing length shown in the several partial courses constituting the reinforcing area.

It will be observed, viewing Fig. 1, that at its base the high splice area is knitted 20 upon a series of needles sufficiently approaching one half the series of needles to constitute and to possess the advantages of what is known in the art as a high splice, which high splice when of full width is 25 knitted at its base upon one half the circle of needles, but which when constituting what is known in the art as a narrow high splice, as here shown, is knitted at its base upon somewhat less than one half the needles. 30 After the stocking has been removed from the machine a mock seam, preferably of sewing stitches, is placed at the back of the stocking through at least the entire extent of the reinforcing or high splice area, 35 that is, from the point 4 to at least the point 9. As here shown, I extend the said seam or line of sewing stitches from a point 10 in the heel to a point 11 at the bottom of the welt or garter top, such seam not only 40 simulating a full fashioned stocking, but partaking of the important function of securing in place and holding flat against the inner face of the stocking the whole series of partial courses of floating yarn. 45

Thus the high splice or other reinforcing area is actually reinforced by the knitted-in portion of the reinforcing yarn and is further reinforced by the floating portions of said yarn, so that in effect there is a triple thickness or fabric substance composed of a main yarn, the reinforcing or high splice yarn knitted in, and the floating portions of said reinforcing yarn.

While I have referred to a line of sewing 55 stitches constituting the mock seam, it is evident that any other suitable seaming means or floating yarn holding means may be employed, but I prefer the sewed seam because the sewing thread actually penetrates or surrounds the various cross portions of the floating thread and binds or secures the same in position.

Having thus described one embodiment 60 of my invention and the best method known to me for producing the same, I desire it to

be understood that although I have used specific terms they are employed in a generic or descriptive sense and not for purposes of limitation, the scope of the invention being set forth in the accompanying claims. 70

Claims—

1. A circular knit or seamless stocking having a knitted reinforcement above the heel whose maximum lateral extent sufficiently approaches one half the circumference of the stocking to constitute a high splice area composed of the main or body yarn and a continuous, non-severed reinforcing yarn knitted in with the main yarn from edge to edge of such reinforcing area, 75 and also floated intact against the inner face of the stocking from and between said edges of the high splice area, and having means structurally distinct from the reinforcing yarn for holding the floated portions 80 thereof intact in position in the completed stocking against its inner face.

2. That method of producing a high splice circular knit or seamless stocking comprising knitting a main yarn or yarns and at the high splice area above the heel introducing a continuous, non-severed high splice yarn and knitting the same with the main yarn for successively increasing portions of successive partial courses until one half the circumference of the stocking is sufficiently approached to form a triangular high splice reinforcement above the heel, the apex whereof is uppermost and at the back median line of the stocking, floating the reinforcing yarn intact from the end of each said partial course of the high splice area to the commencement of the next partial course of said area, and thereafter securing the floated portions of said reinforcing yarn intact and permanently in place against the inner face of the high splice area between the edges of the reinforcement by a distinct line of stitches. 90

3. A circular knit or seamless stocking having a knitted reinforcement above the heel whose maximum lateral extent sufficiently approaches one half the circumference of the stocking to constitute a high splice area composed of the main or body yarn and a continuous, non-severed reinforcing yarn knitted in with the main yarn from edge to edge of such reinforcing area, and also floated intact against the inner face of the stocking from and between said edges of the high splice area, and having means between said edges to hold the floating portions of the reinforcing yarn intact in position in the completed stocking against its inner face. 95

4. A circular knit or seamless stocking having a knitted reinforcement above the heel whose maximum lateral extent sufficiently approaches one half the circumference of the stocking to constitute a high splice area composed of the main or body 100

yarn and a continuous, non-severed reinforcing yarn knitted in with the main yarn from edge to edge of such reinforcing area, and also floated intact against the inner face 5 of the stocking from and between said edges of the high splice area, and a line of sewing stitches at the back median line of the stocking to hold the floating portions of the reinforcing yarn in position intact in the 10 completed stocking against its inner face.

5. A circular knit or seamless stocking having a knitted reinforcement above the heel whose maximum lateral extent sufficiently approaches one half the circumference of the stocking to constitute a high splice area at the back thereof above the heel, composed of a main yarn and a continuous, non-severed reinforcing yarn knitted in with the main yarn throughout 15 gradually increasing portions of successive courses until one half the circumference of the stocking is sufficiently approached to provide a triangular high splice reinforcement the apex of which is uppermost and 20 symmetrical with the back median line of the stocking, the said continuous reinforcing yarn being floated intact from the end of each partial course to the commencement of the next partial course, and a line of 25 sewing stitches at said back median line securing said floating yarn portions intact in place against the inner face of the stocking.

6. That method of producing a high splice circular knit or seamless stocking comprising knitting a main yarn or yarns and at the high splice area above the heel introducing a continuous, non-severed high splice yarn and knitting the same with the main yarn for successively increasing portions of successive partial courses until one half the circumference of the stocking is sufficiently approached to form a triangular high splice reinforcement above the heel, 40 the apex whereof is uppermost and at the back median line of the stocking, floating the reinforcing yarn intact from the end of each said partial course of the high splice area to the commencement of the next partial course of said area, and thereafter securing the floated portions of said reinforcing yarn intact and permanently in place against the inner face of the high splice area by a line of sewing stitches extending along the said back median line of the stocking.

7. A circular knit or seamless stocking

having a knitted reinforcement above the heel whose maximum lateral extent sufficiently approaches one half the circumference of the stocking to constitute a high splice area composed of a main or body yarn and a continuous, non-severed, reinforcing yarn knitted in with the main yarn throughout gradually increasing portions 60 of successive courses to provide a triangular portion, the apex of which is uppermost and symmetrical with the back median line of the stocking, the said continuous reinforcing yarn being floated intact from the 65 end of each partial course to the commencement of the next partial course, so that in each course there exists an uninterrupted series of reinforced loops and a float thread 70 lying against said loops, and a line of sewing machine stitches at said back median line securing said floating yarn portions intact and permanently in place against the 75 inner face of the stocking.

8. A circular knit or seamless stocking having a knitted reinforcement above the heel whose maximum lateral extent sufficiently approaches one half the circumference of the stocking to constitute a tapered high splice at the back thereof above the heel and the base of which tapered high splice is of slightly less length than but is symmetrical with the first course of the heel, the leg of said stocking being composed of a main yarn and a continuous, 80 non-severed, reinforcing yarn knitted in with the main yarn throughout gradually increasing portions of successive courses to provide a triangular portion, the apex of 85 which is uppermost and symmetrical with the back median line of the stocking, the said continuous reinforcing yarn being floated intact from the end of each partial course to the commencement of the next partial course, whereby in each course there is a line of reinforced loops and also a float thread thereagainst, and a line of sewing 90 stitches at said back median line of the stocking, thereby securing the said floating 95 yarn portions intact and permanently in place against the inner face of the stocking, whereby a triple thickness of fabric substance is provided composed of the main 100 yarn, the knitted in portions of the reinforcing yarn and the permanently secured floating portions of said reinforcing yarn.

In testimony whereof, I have signed my name to this specification.

EDWARD C. WILSON.
